UNITED STATES PATENT OFFICE.

CLYDE W. MUMMERY, OF DETROIT, MICHIGAN.

FLUID-FUEL BURNER.

Application filed July 8, 1921. Serial No. 483,245.

To all whom it may concern:

Be it known that I, CLYDE W. MUMMERY, a citizen of the United States, residing at Detroit, in the county of Wayne and State 5 of Michigan, have invented a certain new and useful Improvement in Fluid-Fuel Burners, of which the following is a specification.

My invention relates to improvements in 10 fluid fuel burners and is an improvement on the burner shown and described in Patent Number 1,160,814, issued to me on November 16, 1915.

The object of my invention is to provide 15 a burner of this type having an improved form of steam superheater that is internally provided with a steam expansion area or space that will tend to maintain a substantially constant pressure of steam within 20 the superheater so that the steam will not back up into the generator and tanks or flow too rapidly into the burner pipe to thereby provide an uneven flame.

A further object is provide a hydrocarbon- 25 burner of this class that is simple in construction, reliable and efficient in operation and not expensive to manufacture.

Other and more specific objects will be apparent from the following description taken 30 in connection with the accompanying drawings, wherein—

Figure 1 is a view partly in side elevation and partly in vertical section of a hydrocarbon burner constructed in accordance 35 with my invention;

Fig. 2 is a plan view of the same;

Fig. 3 is a sectional view substantially on a broken line 3, 3 of Fig. 1;

Fig. 4 is an enlarged view in vertical cross 40 section of the superheater taken on line 4, 4 of Fig. 2; and

Fig. 5 is a view in horizontal cross-section substantially on broken line 5, 5 of Fig. 4.

Like reference numerals designate like parts throughout the several views.

Referring to the drawings, the numeral 6 designates a steam superheater, preferably a one piece metal casting of substantially 50 rectangular shape, that has three longitudinally extending cylindrical passageways 7, 8 and 9 arranged along the two sides and in the medial plane thereof, respectively, the passageways 7 and 8 being connected with 55 each other at one end by a cylindrical end

passageway 10 and the passageways 8 and 9 being connected with each other at the end by a cylindrical passageway 11. The passageways 8 and 9 are connected with each other midway between the two ends by 60 a transverse communicating passageway 12 while the passageways 7 and 8 are separated from each other at the inlet end of the superheater by a partition wall 13 and the passageways 8 and 9 are separated from 65 each other at the outlet end of the superheater by a partition wall 14.

Extending lengthwise between the passageways 7, 8 and 9 are two relatively thin, flat plate like portions with a plurality of 70 perforations 17, the plate like portion 16 being interrupted midway between its two ends by the transverse passageway 12 that interconnects the passageways 8 and 9.

The superheater is provided at one corner 75 with a boss 18 that is perforated for the reception of a steam inlet pipe and that communicates with the passageway 7 and such superheater is provided at the diagonally opposite corner and communicating with the 80 passageway 9 with another boss 20 that is perforated for the reception of a steam outlet pipe:

From the above description it will be obvious that the steam entering through 85 the inlet 18 will follow the circuitous course indicated by the arrows through the passageways 7, 10, 8, 12 and 9 to the outlet 20 and will not ordinarily flow through those portions of the passageways 8 and 9 that 90 lie beyond the passageway 12 and are connected by the end passageway 11, said passageway 11 and the adjacent end portions of the passageways 8 and 9 constituting an expansion chamber that will fill with steam 95 and tend to maintain a more nearly constant pressure in the remainder of the superheater by receiving steam if the pressure within the superheater increases and giving out steam if the pressure within the 100 superheater decreases.

The inlet boss 18 of the superheater is connected by a pipe 21 with one end of a steam generator 22 that is preferably oblong cross-sectional shape, as shown in Fig. 105 3, and that is disposed below the superheater in parallel relation thereto. The other end of the steam generator 22 is connected by a pipe 23 with a small receptacle 24 having a vertical partition wall 25 that terminates 110

short of the top thereof and over which water must flow to reach the pipe 23.

The receptacle 24 is connected by a pipe 26 with the lower portion of a closed water regulator cup 27 which, in turn, is connected by a pipe 28 with a water supply tank 30, the pipe 28 having a valve 31 interposed therein by which the flow of water through such pipe may be shut off if desired.

10 The tank 30 is provided with an opening in the top side to permit filling, the opening being arranged to be closed by a screw cap 32 in such a manner as to seal the tank and render the same air tight.

15 The water regulator cup 27 is further connected with a pipe 33 that extends upwardly alongside of the tank 30 and that has its top end bent over as at 34, and projected into the upper portion of the tank 30 so that it will communicate with the space on the interior of such tank. The pipes 28 and 33 both project downwardly into the water regulator cup 27 about half way to the bottom of such cup and terminate in open bottom ends disposed at substantially the elevation in the water regulator cup at which it is desired to maintain the water level.

20 The steam inlet 20 of the superheater is connected by a pipe 35 with one end of a pipe 36 that forms a commingling or gas generating chamber and that extends to the opposite end of the superheater and is thence doubled and extends rearwardly an equal distance and is connected by an elbow member 37 with a burner pipe 38 that is disposed lengthwise below the superheater in the medial plane thereof. The pipe 36 is preferably inclined downwardly throughout its entire length so that fuel will flow freely to 25 the burner pipe 38.

30 The burner pipe 38 is preferably of semi-circular cross-sectional shape and is provided with one row of perforations arranged to direct gasified fuel upwardly and with another row of perforations arranged to direct gasified fuel at an angle against the side of the steam generator 22.

35 The steam generator 22, the burner pipe 38 and the gas generating pipes 36 are supported on brackets 40 that rest within a pan 41 that is perforated around the bottom, as at 42, to afford draft openings, and that preferably has non-inflammable absorbent material, as indicated at 43, disposed in the bottom thereof.

40 The steam generating pipe 36 is connected at its inlet end with a fuel supply pipe 44 of liquid fuel, as kerosene oil, and that may have a valve 45 by which the flow of such fuel to the gas generating pipes 36 may be controlled.

45 If the tank 30 is filled with water and sealed and the cock 31 is then opened water will enter the regulator cup 27 and overflow into the receptacle 24 and steam generator

50 22 until it reaches a high enough level to just submerge the ends of the pipes 28 and 33 when by reason of the minus pressure in the upper end of the tank 30 such water will cease to flow until the ends of the pipes 28 and 33 are again uncovered thereby permitting air to enter the upper end of the tank 30 and water to flow into the regulator cup 27.

55 The partition 25 in the receptacle 24 prevents the water from falling only a short distance below the ends of the pipes 28 and 33 and prevents the water regulator cup 27 from being entirely emptied even if the water is all used out of the tank 30 thus insuring a constant water seal between the tank 30 and the steam generator 36 at all times.

60 In the lighting of the burner, liquid oil is admitted to the pipes 36 and allowed to flow from the pipe 38 into the pan 41 where it is ignited and allowed to burn to heat the burner pipes, superheater and steam generator. As soon as the several parts become sufficiently heated steam will be formed in the generator 22, and will be superheated in the superheater 6 and will mix with the oil that enters the commingling chamber in the pipes 36 in which commingling chamber the oil will be thoroughly gasified and mixed with the superheated steam so that it will 65 issue from the burner pipes as a highly volatile gas that will burn a hot blue flame that will be free from carbon and soot.

70 The superheater 6 will become very highly heated thus tending to expand the steam and create considerable pressure therein but the expansion will equalize variations in steam pressure thereby preventing the steam from backing up or from entering the pipes 36 under varying pressures.

75 The foregoing description taken in connection with the accompanying drawings clearly disclose the form of construction and method of operation of my device, but, while I have illustrated and described what I now consider to be the preferred embodiment of the invention it will be understood that the apparatus shown in the drawings is merely illustrative and that such changes in form, dimensions and arrangement of parts may 80 be resorted to as are within the scope of the following claim.

85 What I claim is:

90 A steam superheater of the class described, comprising a rectangular body portion having three longitudinally arranged spaced apart steam passageways that are connected with each other at the ends to form a continuous conduit from one corner to the diagonally opposite corner of said body portion, said superheater having inlet and outlet means arranged at diagonally opposite corners respectively, and communicating with said passageways, and perforated plate sections extending lengthwise between said 95 100 105 110 115 120 125 130

passageways and terminating short of the ends of said passageways the perforated plate section adjacent the outlet opening having a steam conduit extending crosswise 5 thereof and inter-connecting two of said passageways to thereby permit steam to flow by a shorter course to said outlet opening and to cut off a portion of said passageways so that said cut off portion may serve as an expansion chamber. ¹⁰

In witness whereof, I hereunto subscribe my name.

CLYDE W. MUMMERY.
